UNITED STATES PATENT OFFICE.

JESSE D. LYON, OF CINCINNATI, OHIO, ASSIGNOR TO THE FULNAME COMPANY, OF CINCINNATI, OHIO, A CORPORATION OF OHIO.

GOLF-BALL MARKER.

1,339,569.

Specification of Letters Patent. Patented May 11, 1920.

Application filed March 10, 1917. Serial No. 153,799.

To all whom it may concern:

Be it known that I, JESSE D. LYON, a citizen of the United States of America, and resident of Cincinnati, in the county of 5 Hamilton and State of Ohio, have invented a new and useful Improvement in Golf-Ball Markers, of which the following is a specification.

An object of my invention is to produce 10 an improved golf ball marker in which the ball is rotated in contact with a marking die to receive the impression of the die.

A further object is to produce an improved golf ball marker in which the marking die is adapted to move in a straight line 15 in engagement with a rotatively mounted ball.

These and other objects are attained in the 20 golf ball marker described in the following specification and illustrated in the accompanying drawings, in which:

Figure 1 is a side elevation of my improved golf ball marker.

Fig. 2 is a transverse vertical section of 25 the marker disclosed in Fig. 1.

Fig. 3 is a sectional plan view taken on the line 3—3 of Fig. 1.

Fig. 4 is a plan view of a modified form 30 of marker embodying my invention.

Fig. 5 is a sectional view taken on the line 5—5 of Fig. 4.

Fig. 6 is a sectional view taken on the line 6—6 of Fig. 5.

The marker embodying the principal form 35 of my invention illustrated in Figs. 1 to 3 inclusive, consists of a base 7 having bearing lugs 8 and 9 located respectively at the front and back of the marker, standards 10 and 11 being located at opposite 40 sides of the base, extending upwardly, and bridged at their tops by a member 12. Intermediate the tops and bottoms of the standards 10 and 11 are formed enlargements 13 and 14 in which is journaled a 45 shaft 15 having a handle 16 provided at one end for its rotation. Extending to the rear of bridge 12 and formed integrally therewith is a projection 17 in which an adjustment screw 18 is mounted. In lugs 8 and 9 a shaft 19 is reciprocally mounted, 50 shaft 19 carrying a die block 20 having characters 21 adapted to be impressed into the surface of the ball in order to mark it as will be hereinafter more fully described. 55 The forward end of rod 19 is provided with

a head 22 for more convenient reciprocation thereof. Upon shaft 15 ball socket arms 23 and 24 are provided. Shaft 15 has two portions 25 and 26, 25 being provided with left hand screw threads and the opposite 60 portion 26 being provided with right hand screw threads. The openings in socket arms 23 and 24 which coöperate with the respective portions 25 and 26, are correspondingly screw threaded so that when the shaft is 65 rotated by handle 16 the socket arms will be moved toward or away from one another. Extensions 27 and 28 are provided at the rear of the arms, openings 29 and 30 being formed therein to receive a shaft 31 which 70 is connected with adjustment screw 18 at its lower end 32 as disclosed in Fig. 2. A knurled head 33 is provided on adjustment screw 18 for the purpose of facilitating rotation of the screw. At the forward ends 75 of ball socket arms 23 and 24, pivot pins 34 and 35 are mounted, ball sockets 36 and 37 being rotatively mounted on these pins and being provided with conical recesses 38, 39 for the reception of a golf ball located between them. The sockets may bear against ball bearings 40 and 41 located in ball races formed in the socket arms 23 and 24 and in the sockets 36 and 37. 80

By adjusting the screw 18 to raise or 85 lower the socket arms 23 and 24, the ball located between jaws 36 and 37 may be raised or lowered with respect to the marking die, and by rotating shaft 15 by means of handle 16 socket arms 23 and 24 are 90 brought toward or away from one another, thus pressing or releasing a ball located between them.

The die 20 may be removably mounted on the rod by means of a set screw 42, in order 95 that it may be easily changed for other dies. Rod 19 is preferably square in cross section for the purpose of preventing its rotation when pressure is brought to bear upon the die by the ball to be marked. 100

In the operation of my improved construction, I preferably first ink the characters of the die. Then I move the clamp jaws apart and place a ball between them. Handle 16 controlling the movements of 105 the clamp jaws, is then operated to press the ball between the jaws, which exert upon its surface pressures toward its equator which lies in a vertical plane passing through the characters with which the ball 110

is to be impressed. This insures the surface presenting the proper resistance to the die without distorting the ball. The die carrying rod 19 having been moved 5 to the position disclosed in Figs. 1 to 3 inclusive, adjustment screw 18 is rotated to bring socket arms 23 and 24 downwardly in order to press the surface of the ball into embedding engagement with the characters 10 of the die. With the parts in these positions, pressure is brought to bear upon the head 22 of rod 19 to cause die 20 to move from the front to the back of the base and thereby to rotate the ball, the rotatable 15 clamp in which the ball is mounted, permitting of such rotation. The adjustment screw 18 is then operated to raise the ball above the surface of the characters 21 of the guide 20, so that the ball may be removed 20 and the die moved back to its original position.

In the modified form of my improved ball marker, illustrated in Figs. 4 to 6 inclusive, I have made use of the principle 25 of rotating the ball when the die is reciprocated, but I have not depended on the frictional engagement between the ball and the marking die, for causing rotation of the ball. Instead, I have provided means 30 for positively rotating the ball independently of its contact with the die. In this construction I have provided a base 43, walls 44, 45 and 46, being provided for inclosing the three sides of a chamber in 35 which the ball may rotate, the fourth or front side being open. The top, between walls 44 and 45, is provided with a cover 47 in which a centrally located slot 48 is provided. Immediately below this slot a 40 groove 49 is formed in the base 43. The groove is provided with a reciprocally mounted die holder 50 having side flanges 51 and 52 adapted to aid in supporting it within the groove 49. A centrally located 45 slot 53 adapted to receive a die 54, is provided in the die holder. The die is provided with the usual characters 55, adapted to be impressed into the surface of the ball. Die 54 is reciprocally mounted for vertical 50 movement in slot 53, and for the purpose of reciprocating the die, an eccentric 56 is located below it, as disclosed in Figs. 5 and 6. A handle 57 is provided for rotating the eccentric for the purpose of forcing 55 the die into engagement with the ball. In walls 44 and 45 are formed respective slots 58 and 59 adapted to receive a transversely extending shaft 60 carrying clamp socket arms 61 and 62. At their forward ends, 60 these arms are provided with clamp sockets or jaws 63 and 64, having their ball engaging faces 65 and 66 formed conically for the purpose of gripping and centering the ball. Jaws 63 and 64 are rotatively mounted on 65 the arms 61 and 62 in some such manner as

that above described in connection with the preferred form of my invention. Between socket arms 61 and 62 I have provided a compression spring 69 adapted normally to force the sockets apart, pins 70 and 71 engaging inclined faces 72 and 73 of the respective arms 61 and 62, for limiting the movement of the jaws under pressure of the spring 69. Pins 70 and 71, when shaft 60 is rotated, control the clamping and disengaging movement of the ball sockets 63 and 64, when handle 74, mounted upon shaft 60, is operated. The peripheries of ball sockets 63 and 64, are provided with rack teeth 75 and 76 respectively, which coöperate with 75 respective racks 77 and 78 formed on the under surface of top 47 and on each side of slot 48, additional racks 79 and 80 being provided on the die holder 50 for coöperation with the teeth 75 and 76 of ball sockets 63 and 64. Thus when die holder 50, which carries rod 81 and head 82, is moved, the coöperating ball socket teeth and rack teeth, cause the ball socket to be rotated.

In the operation of this modified form of 90 my invention, the die holder first is moved to the forward position as disclosed in the drawings. The socket arms 61 and 62 are then moved apart by rotating handle 74 and a ball is placed in position between sockets 95 63 and 64. Handle 74 is then moved to cause the ball sockets to clamp the ball tightly. The marking die 54, having previously been placed in position in die block 50, and inked, eccentric 56 is rotated to bring 100 the die to embed its characters into the surface of the ball. The machine is now in condition to be operated. Head 82 is then pushed to cause block 50 to move to the rear of the machine. Upon movement to the 105 rear, the racks 79 and 78 of top 47 of the base, cause rotation of the ball sockets positively and independently of the frictional engagement of the die with the ball. During such a movement, the shaft 60 moves 110 through slots 58 and 59, to the rear thereof. The die block is then pulled to the front of the machine, thus giving the ball a second impression, the characters registering with the impressions previously made by them. 115 As soon as the parts have been restored to their normal positions, the ball clamp is released by means of handle 74, and the ball is removed therefrom.

Having thus described my invention, what 120 I claim is;

1. A golf ball marker comprising a ball clamp, arms adapted to mount the clamp rotatively, a base, means operatively connecting the arms and the base adapted to 125 adjust the arms to clamp a ball located in the clamp when operated, a die holder reciprocally mounted on the base, a die mounted in the die holder, and adjustment means adapted to adjust the position of the 130

arms to bring a ball located in the clamp in engagement with the die located in the holder, whereby the die will be embedded in the ball to cause the ball to rotate when the die holder is reciprocated.

2. In a golf ball marker the combination of two opposed rotatable jaws with ball receiving recesses having inwardly converging walls, means for moving the jaws into contact with the ball whereby the ball is centered and the cover thereof is subjected

to opposing pressures the lines of directions of which meet in the vertical plane of the die, the die and means for mounting the die reciprocally adjacent to the jaws.

In testimony whereof I have hereunto subscribed my name this 8th day of March, 1917.

JESSE D. LYON.
